UNITED STATES PATENT OFFICE.

WILLIAM H. KEPPEL, SAMUEL ANDERSON, AND WILLIAM O. HICKOK, 3RD, OF HARRISBURG, PENNSYLVANIA, ASSIGNORS TO THE W. O. HICKOK MANUFACTURING CO., OF HARRISBURG, PENNSYLVANIA, A CORPORATION OF PENNSYLVANIA.

CARD-FEEDER.

1,058,868.

Specification of Letters Patent. Patented Apr. 15, 1913.

Application filed July 2, 1910. Serial No. 570,151.

To all whom it may concern:

Be it known that we, WILLIAM H. KEPPEL, SAMUEL ANDERSON, and WILLIAM O. HICKOK, 3rd, citizens of the United States of America, and residents of Harrisburg, in the county of Dauphin and State of Pennsylvania, have invented certain new and useful Improvements in Card-Feeders, of which the following is a specification.

This invention relates to certain new and useful improvements in a machine for feeding cards and it is designed more particularly for use as a feeder in connection with card ruling machines, but it will be understood that it may be used for other purposes.

The invention will be herein fully set forth and particularly pointed out in the claims.

In the drawings accompanying and forming part hereof: Figure 1 is a perspective view of our feeder. Fig. 2 is a sectional view of the feed rolls. Fig. 3 is a vertical longitudinal section. Fig. 4 is a detail of the card feeding block. Fig. 5 is a side view of the feeder with part of one of the guides broken away. Fig. 6 is a front view with parts broken away. Fig. 7 is a detail showing the mechanism for operating the members. Fig. 8 is a perspective detail of one of the guides.

Referring now to the details of the drawings by numerals: 1 designates the bed of the machine on which are preferably cast four lugs, 2, 3, 4 and 5 for a purpose to be hereinafter explained. To the outer end of the bed 1 are bolted two uprights 6 and 8 which are connected together both at the top and bottom by cross-bars 9 and 10. These bars 9 and 10 support a central gage 12 which is preferably made of dove-tail shape to fit into a similarly shaped recess in a weight 14 which is adapted to rest upon a pile of cards and descend by gravity as the cards decrease in number as they are fed one by one from the bottom. Owing to the weight being entirely on one side of the gage 12, it will grip the latter and hold to it at any place to which it is adjusted as seen in Fig. 1, but if its outer end rests upon a pile or stack of cards as seen in Fig. 3 and the cards gradually lower, the weight does not grip the gage but will follow the

cards and hold them compressed to the desired extent. Thus the weight when once placed on the cards is self-acting.

The bed 1 is designed to support a pile of cards and these cards rest in the position shown in Figs. 3 and 5. Immediately under their outer ends as seen in Fig. 3, there is a recess in the bed 1 in which is contained an adjustable block 16 which is screwed or secured to a spring plate 18 secured to the under side of the bed. This spring plate 18 normally holds the block 16 so that its upper face is either flush with or slightly above the upper surface of the bed 1, and coacting with the spring plate is an adjusting screw 20, with a locking lever 21, supported by a plate 22, see Figs. 3 and 6. By adjusting this screw 20 the block may be raised to the extent necessary and locked there by the locking lever 21. The aforesaid block 16 is immediately under the gage 12 and the block is intended to be adjusted so that it will permit the passage between it and the gage 12 of one card only of the thickness of cards being fed.

On the extreme ends of the bed 1 are secured two blocks 24 and 26 which form bearings for two feed rollers 28 and 30 which as seen in Fig. 2 are geared together so as to move in unison. The upper of these rollers 28 is spring pressed toward the lower roller 30 by means of a spring 32 so that the rollers will automatically adjust themselves to any thickness of cards fed over the aforesaid adjustable block 16. In order that these rollers 28 and 30 may be positively driven, we secure to one of them, the lower one 30, as shown, a gear 34 which meshes with and is driven from a driving gear 36 to which power is applied in any manner but preferably from the machine to which our card feeder is used to feed cards.

The lugs 2, 3, 4 and 5 hereinbefore referred to are for the purpose of affording bearings for four rods 38, 39, 40 and 41; and the lugs are provided with set screws 42 by which the rods may be clamped in any desired position when adjusted. To these rods are connected horizontal guides 44 and 46 which rest upon the bed 1 and which when the set screws 42 are unscrewed may be adjusted laterally upon said bed until the space between said horizontal guides 44 and

46 is just the width of the cards to be fed by the machine. The outer ends of the horizontal guides 44 and 46 support vertical guides 48 and 50 which, as they are fixed to the horizontal guides 44 and 46, necessarily move with them as they are adjusted. The horizontal guides 44 and 46 also support two more vertical guides 52 and 54, but instead of being fixed these are adjustably secured upon said guides 44 and 46 by means of bolts 56 and wing nuts 58, the heads of the bolts fitting and sliding in grooves 60 in the under side of the guides 44 and 46 while the horizontal portion of the vertical guides 15 52 and 54 have ribs 62 fitting within grooves 64 in the upper sides of said guides 44 and 46; the latter also having slots 66 passing through for the passage of the bolts 56. The construction described is such that 20 when the wing nuts 42 are slightly unscrewed the vertical guides are free to be adjusted along the horizontal guides 44 and 46 in either direction and when in the proper position to feed the proper size cards, 25 said wing nuts 56 are tightened to lock the vertical guides 52 and 54 in position. These vertical guides are furthermore provided with vertical ribs or flanges 68 and 70 which serve to retain the rear edges of the pile of 30 cards, and with slightly inclined horizontal ribs or flanges 72 and 74 which are located over the bed and serve to support the rear ends of the cards, for a purpose to be herein-after stated.

35 The bed 1 is also provided with two longitudinal grooves 76 and 78 and a slot 80, the first two of which serve to receive ribs 82 formed on a slidable feed block 84 which is located on the bed between the horizontal 40 guides 44 and 46. Said slidable feed block 84 has also secured to it a web 86 which passes through the slot 80 in the bed 1, and the web has a flanged bottom 88 from which projects an arm 90, see Fig. 7, by which 45 movement is imparted as will be explained. The slidable card feeding block is formed as shown particularly in Figs. 1, 4 and 7. As there shown it has a wedge shaped front end 92 which is adapted to slide under the 50 bottom of a pile of cards when the latter are supported by the bed and the slightly inclined ribs or flanges 72 and 74, the latter supporting the rear ends of the cards just high enough off of the bed to permit the 55 wedge shaped end 92 of the card feeding block 84 to enter under the bottom card. Said card feeding block 84 is further provided with a recess 94 which is for the purpose of receiving the forward end of an adjustable spring feed plate 96, the rear end 60 of which is rigidly secured by screws 98 to the feed block, and the front end, which owing to the resilient nature of the spring plate would normally project considerably above the wedge shaped end 92, may be

forced down with the recess 94 by means of an adjusting screw 99 until the free end of the spring plate projects above the thickest part of the wedge-shaped end 92 just sufficient to engage with the lowermost card on a pile and shove it from under those above it. It will of course be understood that the adjustment is provided in order that when a thicker card is used the plate 96 may be adjusted to project farther above the wedge shaped end 96, and, likewise, when a pile of very thin cards is to be fed the plate is forced down into its recess 94 until its forward edge projects just sufficient to engage and push the lower card but not to engage the card next above it.

In order to give reciprocatory movement to the card feeding block 84 and also that its movement may be timed with respect to the size of the card and the rapidity with which the card is fed by the feed rollers 28 and 30 hereinbefore described, mechanism is employed as follows: To the bottom of the bed 1 are secured two sets of bearings, 100 and 102, the first of which supports a rock shaft 104 and the other a rotary shaft 106. The latter has splined to it a gear 108 which may readily be removed by unscrewing a wing nut 110 so that gears of different sizes may be employed. This gear meshes with a larger gear 111 journaled on a short shaft 112 removably secured to an arm 114 projecting from the bed 1 as seen in Fig. 6. This arm 114 is slotted at 116 to receive the reduced part of a plate 118 and the shaft 112 may be placed through a gear as 111 and screwed to the said plate 118 when the shaft supports the wheel. And owing to the slot 116, the plate 118 may be adjusted within said slot to bring the wheel 111 into mesh with the small gear 108, said slot permitting adjustment when it is necessary to use a different size gear 108. Power is supplied to the gear 111 by a gear 120 driven from the same shaft which drives gear 36, see Fig. 5. Power is transmitted from the shaft 106 by means of a wrist pin 122 and a connecting rod 124 to an arm 126 secured to the rock shaft 104, so that at each revolution of the shaft 106, the shaft 104 is rocked. The motion from the rock shaft is imparted by a slotted arm 128 to a rod 130 which is adjustably connected both to the slotted arm 128 and to the aforesaid arm 90 projecting from the slidable card feeding block 84. The result of this mechanism is that at each revolution of the shaft 106, the card feeding block is reciprocated in both directions to feed a card and return to position for feeding the next card.

The operation of our feeder is as follows: The horizontal guides 44-46 are adjusted so as to be spaced apart just sufficient to receive between them the cards to be fed to the ruling or other machine. Then the ver-

130

tical guides 52 and 54 are adjusted on the guides 44 and 46 until their ribs or flanges 68 and 70 are spaced away from the vertical gage 12 to receive the cards between them.

5 After this is done, the knife feeding block 84 may be adjusted by moving its arm 90 one way or the other on the rod 130, to bring the block 84 to approximately the proper place. In order to time the throw of the feed block 84 so that the cards may be fed at just the proper intervals, a gear 108 of the proper size is placed on its shaft 106, it being understood that a small card requires a smaller change gear 108 than a larger card, so that for changing the time of the throw, different sized gears 108 are employed. These may be removed and replaced readily by unscrewing the wing nut 110, taking off one gear, replacing it with the desired size, and again securing the wing nut 110. It is to accommodate the use of different change gears 108 that the bracket 114 which supports the larger gear 111 is slotted, this slot being formed on 25 an arc struck from the axis of the driving wheels 36 and 120. Further adjustment is provided by changing the "throw" of the arm 128, as will be understood. The various adjustments being made, a pile of cards 30 of the appropriate size is placed on the bed as indicated in Fig. 5, the rear ends of the cards resting on the slightly inclined ribs or flanges 72 over the wedge-shaped part 92 of the card feeding block 84. Now at 35 each revolution of the shaft 106 the card feeding block 84 is fed forward under the pile of cards and its spring plate 96 (which has been properly adjusted) strikes against the bottom card and shoves it from under 40 the pile so that its other end is moved to the feed rollers 28 and 30, when these rollers feed the card forward into the machine for ruling it. The card feeding block 84 now returns and the operation is repeated, the 45 cards being fed one by one as long as they last.

We are aware that it is not new to employ a feeding device in which a reciprocating feeder moves the lowermost card from a pile of cards and feeds it to a pair of feed rollers and therefore do not claim this broadly.

What we claim as our invention is:

1. In a machine of the character described, a bed, vertical guides thereon adjustable to and from each other and having vertical and horizontal ribs or flanges, the vertical ones acting as a guide for the rear edges of the cards and the horizontal ones located slightly above the bed to support the rear part of the cards slightly above the bed.

2. In a machine of the character described, a bed, vertical guides thereon adjustable to and from each other and having

vertical and horizontal ribs or flanges, the vertical ones acting as a guide for the rear edges of the cards and the horizontal ones located slightly above the bed to support the rear part of the cards slightly above the bed, and a card feeding block slidably supported on said bed and having a wedge shaped portion movable under said cards and another portion arranged to strike and shove the bottom card from under the others. 75

3. In a machine of the character described, a bed, guides thereon having means located slightly above the bed for supporting the rear part of the cards slightly above said bed, and a card feeding block slidably supported on said bed and having a wedge shaped portion movable under said cards with a recess behind the wedge-shaped portion and a part located in said recess and adjustable with respect to said wedge, the latter being arranged to enter under a pile of cards and the said adjustable part being arranged to strike and shove the bottom card from under the others. 80

4. In a machine of the character described, a bed, guides supported thereon longitudinally of the bed and movable to and from each other, and vertical guides supported by said longitudinal guides and adjustable thereon and having ribs or flanges 90 adapted to hold the edges of the cards slightly above the bed in combination with a card feeding block slidably supported on the bed and having its end movable under the cards supported on said ribs or flanges. 95

5. In a machine of the character described, a bed, a gage at the front of said bed, longitudinal guides supported on the bed and adjustable to and from each other, and vertical guides supported on said longitudinal guides and adjustable thereon to and from said gage, said vertical guides having ribs or flanges, in combination with a card feeding block slidably supported on the bed and having its end movable under the cards supported on said ribs or flanges. 100

6. In a machine of the character described, a bed having lugs projecting therefrom on opposite sides of the bed, guides running longitudinally of the bed and having rods projecting through said lugs whereby said longitudinal guides may be adjustable on the bed, vertical guides adjustably supported on said longitudinal guides and a gage near the front of the bed, the vertical guides being adjustable on the longitudinal guides to and from said gage. 115

7. In a machine of the character described, a bed having lugs projecting therefrom on opposite sides of the bed, guides running longitudinally of the bed and having rods projecting through said lugs whereby said longitudinal guides may be adjustable on the bed, vertical guides adjustably supported on said longitudinal guides and 120

a gage near the front of the bed, said gage having a weighted part slidably supported thereon to bear down upon the cards.

8. In a machine of the character described, a bed having means for feeding cards or the like, guides for controlling the position of said cards, a gage at the front of the machine, and an adjustable block projecting through the bottom of the bed and 10 coacting with said vertical gage, and a spring plate for supporting said block.

9. In a machine of the character described, a bed having means for feeding cards or the like, guides for controlling the 15 position of said cards, a gage at the front of the machine, and an adjustable block projecting through the bottom of the bed and coacting with said vertical gage, a spring plate for supporting said block and a screw 20 for controlling the position of said plate.

10. In a machine of the character described, a bed, guides for controlling the position of cards or the like, and a reciprocating feeding block comprising a wedge-shaped member with a recess in the block at 25 the rear of the wedge, and a spring element having one end located in said recess with its front end projecting above the rear part

of said wedge, and means for adjusting the spring element so that its front edge may 30 be moved with respect to the rear part of the wedge, whereby the said wedge may pass under a pile of cards, and the projecting spring element strike against and move the bottom card from under the pile. 35

11. In a machine of the character described, a bed, guides for controlling the position of cards or the like, and a reciprocating feeding block comprising one member adapted to slide under the cards and 40 having a recess therein and a spring plate adjustably secured to the first member and having its end in said recess with its end projecting above the same whereby when the member slides under the cards the part of 45 the spring plate projecting from the recess strikes against the card and feeds it.

Signed at Harrisburg, Pa. this 29th day of June 1910.
